APPARATUS FOR THE PRODUCTION OF ARTIFICIAL THREADS BY THE WET SPINNING PROCESS

Rupert Sydney Jones, Grimsargh, near Preston, England, assignor to Courtaulds Limited, London, England, a British company

Application August 2, 1944, Serial No. 547,770
In Great Britain October 6, 1943

3 Claims. (Cl. 57—76)

1

This invention relates to apparatus for the production of artificial threads by the wet spinning process in which the thread, after leaving the spinning bath, is passed over one or more godets and led by means of a reciprocating funnel into a centrifugal spinning box. In such an apparatus, it has hitherto been the practice to suspend the funnel by means of a funnel bracket which grips the upper end of the funnel while the lower end thereof is situated, and reciprocates vertically, inside the box, so that the thread is laid in a spiral path forming an annular cake. When using this method of collecting the thread, it is highly desirable that the lower end of the funnel shall remain in the centre of the box, that is to say, it shall reciprocate so that the centre of the lower end of the funnel shall coincide with the axis of rotation of the box, since otherwise the thread is liable to contain kinks or curls, which give rise to weak places in the finished thread. This maintenance of the end of the funnel exactly in the line of the axis of the box has hitherto not been an easy matter, since shaking of the machine may tend to move the funnel end away from the centre, and further, the replacing of the funnel and funnel bracket after the periodic removal of the same, which is necessary when emptying the cake out of the box, may easily lead to the funnel being put into a position more or less out of the centre.

I have now found that I can obtain good results when collecting a thread in a centrifugal box if the funnel be suspended loosely by a support situated approximately in the same horizontal plane as the centre of gravity of the funnel. I find that if the funnel be suspended in this manner, and if for any reason the lower end of the funnel be moved away from the centre line in which lies the axis of rotation of the box, the pull of the thread, as it passes down the funnel into the box tends to bring the end of the funnel into the centre again. The particular method of suspending the funnel may vary considerably, provided the above mentioned condition is observed. For instance, the top of the funnel may be provided with a heavy ring of metal, so that the centre of gravity of the whole lies in a horizontal plane passing through a part of the cone of the funnel, and the funnel is then passed through a ring supported by the funnel bracket until that part of the funnel in which the centre of gravity lies rests on the said ring. Or the stem of the funnel may be provided with a conical collar with the base of the cone nearer the top of the funnel, the collar being situated around the

2

centre of gravity. The funnel bracket is then provided with a ring slightly larger in diameter than the stem of the funnel, so that, when the funnel is inserted through this ring, the conical collar rests on the ring and the point of suspension is in the same horizontal plane as the centre of gravity of the funnel. Any other suitable suspension may, however, be employed such for instance as a hemisphere attached to the funnel supported on a circular line, three point or spherical surface.

The accompanying diagrammatic drawing illustrates the present invention although the invention is not limited to the particular forms shown. Figure 1 shows a vertical section of a funnel and a centrifugal spinning box and Figure 2 a vertical section of the top of a funnel.

Referring to Figure 1, the spinning funnel 1 through which the thread passes continuously into the spinning box 4, has a cone-shaped part 2 and constrictions 3 in the stem of the funnel. The lower end of the funnel 1 terminates inside the box 4 which is provided with a lid 5. Inside the box 4 the cake of thread 6 builds up against the inner wall. The cone-shaped part 2 of funnel 1 rests with approximate line contact on the metal ring 7 in the top of the bush 8. The bush 8 screws into the support 9 which is reciprocated. The top of the cone-shaped part 2 of funnel 1 is provided with a heavy metal annular member 10 of such a weight that the centre of gravity of the funnel 1 lies approximately in the same horizontal plane as the metal ring 7. The member 10 is fastened to the top of the funnel in any convenient way, for example, with sulphur.

Figure 2 shows a modification of the method of suspending the funnel according to the present invention. The cone-shaped part 2 of the funnel 1 is provided with a metallic collar 11 which terminates in a hemisphere 12. The top of the bush 14 is cut away to receive the hemisphere 12. The weight of the metallic collar 11 and the hemisphere 12 is such that the centre of gravity of the funnel 1 lies approximately in the same horizontal plane as the top of the bush 14.

When using the apparatus of the present invention the thread 13 passes down the centre of the funnel 1 into the spinning box 4. The funnel 1 is reciprocated through the support 9 so that the thread 13 is laid up inside the rotating box in the form of the cake 6. The funnel 1 reciprocates so that the centre of the funnel 1 coincides with the axis of rotation of the box 4. If, during collection of the thread, the funnel moves away from the centre line the pull of the thread will

bring the funnel back into the centre line again so that the cake 8 formed in the box 4 will be comparatively free from kinks and curls. Locating the centre of gravity in the same horizontal plane as the point of suspension prevents the lower end of the funnel from dragging on the yarn.

What I claim is:

1. Apparatus for the collection of thread in a centrifugal spinning box comprising a support and a funnel loosely suspended in the support, in combination with a collar on the funnel above the point of support which collar is of sufficient mass to locate the center of gravity of the funnel substantially in the horizontal plane of its suspension whereby the lower end of the funnel tends to stay axially central of the spinning box.

2. Apparatus for the collection of thread in a centrifugal spinning box comprising a support and a vertically reciprocating funnel loosely suspended in the support, in combination with a

collar on the upper end of the funnel above the point of support which collar is of sufficient mass to locate the center of gravity of the funnel substantially in the same horizontal plane as its suspension whereby the lower end of the funnel does not drag on the yarn.

3. Apparatus for the collection of thread in a centrifugal spinning box comprising a support and a vertically reciprocating funnel loosely suspended in the support on an approximate line contact, in combination with a metal collar on the upper end of the funnel above the point of support which collar is of sufficient mass to locate the center of gravity of the funnel substantially in the same horizontal plane as its suspension whereby the lower end of the funnel does not drag on the yarn and the lower end of the funnel tends to stay axially central of the spinning box.

RUPERT SYDNEY JONES.
